(57) **CLAIM**

The ornamental design for a display screen or portion thereof with a graphical user interface, as shown and described.

DESCRIPTION

FIG. 1 illustrates a front view of a display screen or portion thereof with a graphical user interface displaying a first image, in accordance with an embodiment; and,

FIG. 2 illustrates a front view of a display screen or portion thereof with a graphical user interface displaying a second image, in accordance with the embodiment.

The appearance of the transitional image sequentially transitions between the images shown in FIGS. 1 and 2.

The outer broken line showing of a display screen and the other broken lines showing portions of the graphical user interface are included for the purpose of showing portions of the article which form no part of the claim.

1 Claim, 2 Drawing Sheets
